US0D1050742S

(12) **United States Design Patent** (10) Patent No.: **US D1,050,742 S**
(45) Date of Patent: ** Nov. 12, 2024

(54) **LAMINATE**

(71) Applicant: **PANTEX INTERNATIONAL S.P.A.**,
Trezzano Rosa (IT)

(72) Inventor: **Pietro Angeli**, Trezzano Rosa (IT)

(73) Assignee: **PANTEX INTERNATIONAL S.P.A.**,
Trezzano Rosa (IT)

(**) Term: **15 Years**

(21) Appl. No.: **35/516,864**

(22) Filed: **Apr. 14, 2022**

(80) **Hague Agreement Data**

Int. Filing Date: **Apr. 14, 2022**

Int. Reg. No.: **DM/220589**

Int. Reg. Date: **Apr. 14, 2022**

Int. Reg. Pub. Date: **Apr. 14, 2023**

(30) **Foreign Application Priority Data**

Oct. 15, 2021 (EM) 008726087-0001
Oct. 15, 2021 (EM) 008726087-0002
Oct. 15, 2021 (EM) 008726087-0003
Oct. 15, 2021 (EM) 008726087-0004
Oct. 15, 2021 (EM) 008726087-0005
Oct. 15, 2021 (EM) 008726087-0006

(57) **CLAIM**

The ornamental design for a laminate as shown and described.

DESCRIPTION

1. Laminate

1.0 Top

The dot dash broken lines depict the boundaries of the claim and form no part thereof.

In the figure, the black dots and the areas filled with black color depict portions of the laminate that form no part of the claimed design.

1 Claim, 1 Drawing Sheet
